UNITED STATES PATENT OFFICE.

EMERY H. SMITH, OF BURTON, MICHIGAN, ASSIGNOR OF FORTY-FIVE ONE-HUNDREDTHS TO CHARLES J. JORDAN, OF OWOSSO, MICHIGAN.

COMBINED INVALID BED AND CHAIR.

1,283,578.

Specification of Letters Patent.

Patented Nov. 5, 1918.

Application filed December 6, 1917. Serial No. 205,780.

To all whom it may concern:

Be it known that I, EMERY H. SMITH, a citizen of the United States, residing at Burton, in the county of Shiawassee and State 5 of Michigan, have invented certain new and useful Improvements in Combined Invalid Beds and Chairs; and I do hereby declare the following to be a full, clear, and exact description of the invention, such as will enable others skilled in the art to which it 10 pertains to make and use the same.

This invention relates to improvements in combined invalid beds and chairs.

The object of this invention is to improve 15 the construction of an invalid bed and chair so as to render the bed capable of being moved to an inclined position to permit the patient to be in a sitting position without bodily touching the invalid.

20 A still further object of this invention is to provide a combined invalid bed and chair which is equipped with means whereby the bed may be raised to an inclined position to permit the patient to readily sit up and be 25 supported in sitting up position without bodily touching the invalid or person.

30 A still further object of this invention is to provide a combined bed and invalid chair which is equipped with novel means whereby the bed may be readily moved to an inclined position so as to give the patient a rest.

35 A still further object of this invention is to provide a combined bed and invalid chair which includes a frame having movable part therein and means to move the parts for raising it from a bed into an inclined chair.

40 A still further object of this invention is to provide a combined invalid bed and chair of this character, which will be simple, practical and comparatively inexpensive in construction and one that can be manufactured and sold at a low cost.

45 With these and other objects in view, the invention consists in the novel combination and arrangement of parts hereinafter more fully described and set forth in the claims hereto appended.

In the drawings:

50 Figure 1 is a perspective view of a combined invalid bed and chair illustrating the bed in an inclined position to represent the chair.

Fig. 2 is a side elevation of the same representing the bed.

55 Fig. 3 is a longitudinal sectional view

illustrating the bed raised to an inclined position.

Fig. 4 is a transverse sectional view.

Fig. 5 is a transverse sectional view taken through the seat portion of the bed when in 60 raised position.

Like numerals of reference designate corresponding parts in all the figures of the drawings.

Referring to the drawings, the numeral 5 65 indicates a combined invalid bed and chair in its entirety and it includes the spaced parallel side rails 6 which are connected at one end by the end rail 7. The opposite ends of the side rails 6 are provided with bearings 8 70 which are secured thereto at the upper edges thereof. A U-shaped brace 9 has the terminals of its arms secured as at 10 to the supporting legs 11 which legs are secured to the side rails 6 at the open end thereof. The 75 rear or other ends of the side rails are supported by legs 12 which are secured to the end rail thereof. A roller 13 has mounted therein a shaft 14, the ends of which shaft project beyond the end of the roller and are 80 journaled in the bearings 8, as illustrated in Fig. 1 of the drawings. The side rails 15 are secured to the opposite ends of the roller and are movable between the side rails 6 of the frame. A brace 16 is secured to the 85 lower edges of the side rails 15 at the free ends thereof to reinforce and hold the rails connected together. A flexible strip 17 is secured to the upper edges of the side rails 15 and to the roller 13 as at 18 and this 90 construction constitutes the foot portion of the bed when in a horizontal position.

An L-shaped bracket 19 is secured by one end, as at 20, to the under side of each side rail 6 and depends downwardly therefrom 95 and the brackets have their free ends directed inwardly in the direction of each other as at 21, thereby constituting supports.

The shaft 14 carried by the roller 13 has 100 secured to one end a wheel 22 located on the exterior of one side rail 6, the purpose of which will be hereinafter more fully described.

A vertical support 23 is secured as at 24 105 to the inner side of the end rail 7 and rises vertically therefrom to constitute the head board of the bed.

The bed includes the side rails 25 having one end connected by an end rail 26, and 110

secured to the upper edges of the side and end rails of the bed is a flexible member 27 which constitutes a mattress. The forward edges of the side rails 25 have connected thereto on the lower edges thereof a reinforcing brace 28 and the portions of the side rails 25 are severed from connection with the side rails 6, thus constituting a seat 29 formed by a portion of the side rails 25 and flexible member 27. The forward edges of the side rails 27 are provided with supporting members 30 which are adapted to engage the under edges of portions 29 of the seat when in a horizontal position to support the same in its horizontal position and thus provide the bed.

A crank shaft 31 has its ends journaled in the side rails 25 of the bed and extended through the side rails 6 of the frame, as illustrated. A gear wheel 32 is secured to one end of the crank shaft 31 on the exterior of one side rail 6 and this wheel 32 is provided with ratchet teeth 33 which are adapted to be engaged by a dog 34 pivotally secured to the side rail 6 as at 35. A crank handle 36 is secured to the shaft 31 on the exterior of one side rail and the wheel 32 and when turned in a clockwise direction it will move the bed to an inclined position, moving the seat into engagement with the portions 21 of the brackets 19 and thus constituting a seat and permitting the patient to be readily moved into an inclined or sitting position.

35 A lever 37 or rod is eccentrically and pivotally secured to the wheel 22 as at 38 by one end and has its opposite end eccentrically and pivotally secured to the wheel 32 as at 39. Thus it can be seen that by movement of the wheel 32 through the medium of the crank 36 the foot portion of the bed 15 will be moved into an inclined position when the bed is elevated, and moved to a horizontal position when the bed is lowered.

45 A supporting rod 40 has its end provided with a semicircular bearing 41 which is journaled on the crank portion of the shaft 31 as at 42, and the opposite end is bent angularly and is secured to the end rail 26 of the bed as at 43 to reinforce and position the bed and support the bed in either of its positions.

A pair of braces 44 are secured to the under side of each side rail 6 intermediate the ends thereof and are adapted to extend beyond the inner or side wall thereof to permit the bed to be readily supported in a horizontal position and lowered. A pawl 46 is pivotally secured as at 47 to the side rail 6 and is adapted to engage the ratchet teeth 33 to normally hold the bed in its raised inclined position as illustrated in Fig. 1 of the drawings.

In operation, the handle is grasped and rotated in a clockwise direction, thus rotat-

ing the wheel 22, moving the bed to an inclined position, positioning the seat upon the brackets 21 and at the same time lowering the foot portion 15. The patient is then in an upright or sitting position. When it 70 is desired to permit the patient to lie down, it is only necessary to release the dogs 46 and 34, grasp the lever and let the patient down easily until the bed is in a horizontal position and the foot portion is raised flush 75 therewith. Such operation is done simultaneously through the medium of the wheels 22, and 32 and the rod 37.

Having thus described my invention what I claim is:

1. A combined bed and chair including a main frame, a bed frame journaled in the main frame, said bed frame including a seat portion and a body portion, said seat portion being hinged to the body portion, an independent foot portion journaled to the foot end of the main frame, and means for raising the body and simultaneously lowering the seat and foot portions.

2. A combined bed and chair including a main frame, a bed frame having a hinged portion constituting a seat, said bed frame journaled in the main frame, an independent foot portion journaled in the foot end of the main frame, and means carried by the main frame and connected to the bed frame and foot portion to raise the bed frame and simultaneously lower the foot portion.

3. A combined bed and chair including a main frame, means for supporting the frame, 100 a foot portion journaled in one end of the frame, an independent bed frame journaled intermediate the ends of the frame, said bed frame including a seat portion hinged thereto, means for supporting the seat portion 105 in a horizontal position when the bed portion is raised, and means for raising the bed portion and simultaneously lowering the foot and seat portions.

4. A combined bed and chair including a main frame, legs supporting the main frame, a bed portion journaled in the main frame, a seat portion hinged to one end of the bed portion, an independent foot portion journaled to the foot end of the frame, means 115 for raising and lowering the bed portion and moving the seat portion into seat actuating position and bed actuating position, and means connected to the first named means for moving the foot portion simultaneously 120 with the movement of the bed and seat portions.

5. A combined bed and chair including a main frame, means for supporting the main frame, a crank shaft journaled in the main 125 frame, a bed frame carried by the crank shaft, said bed frame comprising a seat portion and back portion, said seat portion being hinged to the back portion, means for raising the back portion to an inclined posi-

tion, and means for supporting the seat portion when the bed is raised to an inclined position, a foot portion journaled in the main frame, and means connected to the 5 crank shaft and foot portion for raising back portion and simultaneously lowering the seat and foot portions.

6. An invalid bed comprising a main frame, legs supporting the main frame, a bed 10 portion journaled in the main frame and including hinged connecting back and seat portions, a separate foot portion journaled to the foot end of the main frame, means for raising and lowering the bed portion and 15 moving the seat portion into seat actuating position and to bed actuating position, means for moving the foot portion downward and away from the seat portion, when the same is moved to seat position, and means for connecting the foot portion with the bed portion 20 for simultaneous movement therewith, as and for the purpose specified.

7. An invalid bed comprising a main frame, means for supporting the main frame, 25 a crank shaft journaled in the main frame,

a bed frame carried by the crank shaft, a rod rigidly secured to one end of the bed frame and engaging the crank shaft, said bed frame comprising a seat portion and a back portion, said seat portion being hinged 30 to the back portion, means for raising the back portion to an inclined position, means for supporting the seat portion when the bed is raised to an inclined position, a ratchet wheel secured to the shaft, dogs engaging 35 the ratchet wheel to hold the same in locked position against accidental movement, a second shaft journaled in the foot end of the main frame, a foot portion secured to the second shaft, a wheel secured to the second 40 shaft, and a rod operatively connecting the ratchet wheel and the second mentioned wheel, as and for the purpose specified.

In testimony whereof I affix my signature in presence of two witnesses.
